UNITED STATES PATENT OFFICE.

CHARLES M. FULKERSON, OF CLEVELAND, OHIO.

APPARATUS FOR CARBURETING AIR.

SPECIFICATION forming part of Letters Patent No. 394,480, dated December 11, 1888.

Application filed October 5, 1887. Serial No. 251,531. (No model.)

To all whom it may concern:

Be it known that I, CHARLES M. FULKERSON, a citizen of the United States, residing at Cleveland, in the county of Cuyahoga and 5 State of Ohio, have invented certain new and useful Improvements in Apparatus for Carbureting Air, of which the following is a specification.

My invention relates to that class of air-carbureting apparatus in which a pump is employed to force the air into the carburetor, said pump consisting, essentially, of a series 10 of bellows arranged around a common center and adapted to be operated upon alternately by suitable mechanism, so that a constant supply 15 of air to the carburetor is insured through suitable pipe-connections.

My invention consists in features of novelty to be hereinafter fully described, and 20 then specifically pointed out in the claim.

In order that my invention may be fully understood, I will now proceed to describe the same with reference to the accompanying drawings, in which—

25 Figure I is a side elevation of a complete gas-making apparatus with my improved air-pumping apparatus used in connection therewith, part of the operating mechanism being broken away. Fig. I^a is a plan of the pump-casing with its top mechanism omitted. Fig. II is a vertical section on line x x, Figs. I^a and IV. Fig. III is a detail sectional view on line III III, Fig. I^a. Fig. IV is a horizontal section on line Y Y, Figs. I^a and II. Fig. V is a vertical section on line Z Z, Fig. II. Fig. VI is a vertical section of one of the valves of the bellows. Fig. VII is a vertical section of one of the valves controlling the outlet of air.

Referring to the drawings, A represents my 40 improved air-pump, B the carburetor, and C the mixer, all of which have suitable pipe-connections, as shown, with each other.

D is a pipe leading from the pump to the carburetor, and provided with a valve.

45 E is a pipe for the vaporized air leading from the carburetor to the mixer C, which is also provided with a valve.

F is an auxiliary pipe leading from the main air-pipe D to the mixer, and also provided 50 with a valve. This auxiliary pipe is for the purpose of supplying an additional quantity

of air to the vaporized air within the mixer, when desired.

G is the distributing-pipe leading from the mixer.

55 A detailed description of the system just outlined is not necessary to enable those skilled in the art to use my invention, which lies principally in the air-pumping apparatus. It should be understood that my pump can be 60 used with any system wherein a pump is used for forcing air into the carburetor.

Referring now to said pump, a represents the cylindrical sheet-metal casing resting on legs b. The casing is strengthened by annular castings c c' at the top and bottom, respectively, provided with perforated lugs d d', respectively, for the passage of the bolts or rivets e, wherewith the casing is secured to said castings. Between the ends of the casing at 65 suitable intervals are arranged other castings, f, whereto the casing is bolted or riveted. Strengthening-ribs g, forming chords of a circle, are cast with said annular castings, and afford means for the attachment of bellows h, of 70 which five are shown, being arranged around a common center. The movable leaves h' of the bellows are hinged to the fixed leaves h² thereof at h³, said leaves extending almost the entire height of the casing. The movable 75 leaves of the bellows have secured thereon brackets i, provided with perforated ears i', for the passage of bolts i². Secured between said ears by said bolts are arms j, which radiate from crank-arm k, secured removably on 80 the vertical shaft k'. Forming a part of the upper annular casting, c, is a diametrical cross-piece, c², depending from which is a supporting-bracket, l, perforated for the passage of shaft k'. Said shaft is supported in said 85 bracket by a removable collar, k². For keeping the arms j on the crank-arm is a removable collar, k³, on the end of the latter. At the upper end of shaft k', above the cross-piece c², is a gear-wheel, m, meshing with gear-wheel n' on the horizontal shaft n, mounted 90 in suitable bearing-blocks, o o', on the cross-piece c². Loosely fitted on said shaft n, is a windlass, p, having a hollow trunnion, p', fitting on the outer end of shaft n, and which 95 also bears in block o'. Said trunnion is squared at its end at p² to fit in a square socket 100

of crank Q, for turning the windlass to wind the rope thereon. A ratchet-wheel, R, having a collar, S, fitting on the shaft n, is secured to said shaft by a pin, T, passing through the latter and said collar. Adapted to engage said ratchet-wheel is a pawl, U, pressed into engagement with the teeth thereof by a spring, V, so that when the rope is being wound on the windlass the shaft will not turn therewith, but when the rope is wound up and the apparatus started both will revolve. A rope, W, is adapted to be coiled around the windlass and to revolve the windlass through the medium of weight r and the usual pulley mechanism, s. On shaft n is keyed a hand-wheel, t, which is used when it is necessary to keep the pump going while the rope is being wound on the windlass. The fixed leaves of the bellows are provided with air-inlet valves u. Leading downward from the fixed leaves of the bellows are metallic exit-pipes v, which converge into a common metallic trunk or chest, w, in the center of the bottom of the casing, to which is connected the pipe

D, leading to the carburetor B. Check-valves x are located in the horizontal portions of pipes v to prevent the air going from one bellows to the other. The bottom of the casing may be closed by means of semi-disks y y'. The top of the casing may be closed by flanged semi-disks z z'.

Having thus described my invention, the following is what I claim as new therein and desire to secure by Letters Patent:

The combination, with the annular casing a, of the two annular castings c c', arranged within said casing at its top and bottom, respectively, and having the lugs d and pins e for securing the casing to them, the diametric cross-piece c², having the perforation for the passage of a shaft, and the semi-disks y y' and z z', detachably secured to the lower and upper castings, substantially as set forth.

CHARLES M. FULKERSON.
